COATING MACHINE

Harry Phillips, Beverly, Mass., assignor to United Shoe Machinery Corporation, Flemington, N. J., a corporation of New Jersey

Application June 5, 1943, Serial No. 489,831

22 Claims.

(Cl. 12—80)

This invention relates to coating machines and is herein illustrated as applied to a machine, for coating the inner channel and the side face of the rib of an insole to which a strip of reinforcing material is to be applied, of the type shown in Letters Patent of the United States No. 2,307,793, granted January 12, 1943, upon the application of Joseph R. J. Ioannilli.

When it is desired to reinforce an insole by strips of fabric material adhering to the inner side of the rib and extending across the inner channel, it is important that the adhesive coating material shall be well distributed by the coating machine, upon the angularly related surfaces of the rib and the channel and as well upon a portion of the midsurface of the insole. Furthermore, such machines, to be commercially practical, must feed the work at a considerable speed and, in so doing, it is found that there is danger that the flow of adhesive to be applied to the work will not start immediately and, consequently, that there will be a short portion of the length of that peripheral area which is to be coated which will be bare.

Consequently, an important object of the invention is the provision of an organization affording still further assurance of an adequate flow of coating material at the very beginning of the feeding movement.

Consistent with that object, a feature of the invention resides in mechanism for momentarily providing an excess of coating material at the point of application at the beginning of an operation upon a piece of work.

In machines for coating small pieces presented one after another, it is usually desirable to separate the parts of the work-feeding mechanism to facilitate the introduction of a piece of work and to provide operator-controlled mechanism for both causing the feed mechanism to grip the work and starting the flow of coating material. Still another feature of the invention resides in such an operator-controlled means, illustrated herein as utilized to open a valve controlling the supply of coating material momentarily beyond its normal operating position as the work is presented to the machine and then to return the valve, after a brief interval, to an operating position where the valve opening is sufficient for the normal supply of coating material.

As illustrated, the valve-operating mechanism is provided with a latch designed to hold it open in its normal operating position, and operator-controlled mechanism, such as a treadle, is provided with a cam which will push the valve be-

yond its normal position and then release it for retention by the latch in its normal operating position. Preferably, also, the latched position is made adjustable.

These and other features of the invention will best be understood from a consideration of the following specification taken in connection with the accompanying drawings, in which

Fig. 1 is a side elevation of the machine;

Fig. 2 is a plan view of levers embodied in a treadle mechanism;

Fig. 3 is an angular view of the operating parts of the machine, showing a piece of work in coating position;

Fig. 4 is an angular view of an insole which has been coated in this machine and showing a short piece of the reinforcing tape already applied;

Fig. 5 is a side elevation, on a larger scale than Fig. 1, showing the parts of the machine which are near the work;

Fig. 6 is an angular view of a portion of the nozzle removed from its working position;

Fig. 7 is an end view of the machine taken from the left in Fig. 1;

Fig. 8 is a front elevation, greatly enlarged, of the nozzle;

Fig. 9 is a horizontal section on the line IX—IX in Fig. 8; and

Fig. 10 is a vertical section on the line X—X in Fig. 8.

Referring particularly to Figs. 3 and 4, there is shown an insole I which has been channeled to provide an upstanding rib 10, and to which adhesive coating material has been applied on the inner surface of this rib and on the adjacent channel 12, as well as on a portion of the midsurface 14, to make sure that there is sufficient width of adhesive to firmly attach the inner edge of a reinforcing tape 16 the other edge of which is flush with the top of the rib. When such a piece of work is in position in the machine, as in Fig. 3, the feather 18 of the insole is gripped between a driven upper feed wheel 20 and a lower feed wheel 22 (Fig. 5), while a coating is applied by means of a nozzle 24 and distributed by a brush 26. Assurance of the proper coating of the inner surface of the rib is given by the employment of a freely rotatable spindle 28 having at its lower end a frusto-conical portion 30 provided with spiral ribs. This portion 30 bears against the inner face of the rib and holds it against the frusto-conical end face 32 (Fig. 5) of the upper feed wheel 29. Control of the flow of coating material to the nozzle from a source

55 of supply (not shown) as by gravity through a

flexible tube 34 is effected by a valve rod 36 (Fig. 10), having a conical end, in a way which will be later more fully described.

As more particularly shown in Fig. 1, the upper feed wheel 20 is mounted on the end of a shaft 40 extending through an arm 42 which is attached to the end face of a hollow frame 44 which may be supported in any desired manner, such as by a column 46. The lower wheel 22 is carried by a shaft 48 journaled in an arm 50. This arm is swingably mounted by means of pivot screws 52 carried in flanges 54 forming part of the frame, thereby permitting the lower wheel 22 to be raised into gripping engagement with the work. The two shafts are interconnected by gears 56 and 58, and power is supplied to the machine through a drive shaft 60 which receives power from any suitable source (not shown) and is connected to the upper shaft 40 by speed-reducing gears 62 and 64. When the machine is in use, these shafts and the feed wheels will be continuously rotated.

To facilitate the entrance of work into the machine, the nozzle 24 is mounted upon a swinging frame 70 carried on a pivot pin 72 which is supported by two arms 74 and 76 (Figs. 3 and 7) which form part of an extension 78 attached to the top of the frame 44. This swinging frame 70 is provided on its end face with a vertically disposed groove 80 in which there is received a U-shaped block 82 held at the right height by screws 84 (Fig. 5) passing through slots in the swinging frame 70. The horizontal lower portion 86 of this U-shaped block 82 has a downward extension 86' to provide the front face of the nozzle 24 and to this there is attached a nozzle block 90 (Fig. 6) cut away to make room for the spindle 28 and having a recess 92 leading downward toward an outlet opening 94 (Fig. 10). Preferably, a shallow dam 93 (Figs. 8 and 10) extending between the points 96 and 98 keeps the recess 92 filled at all times. Since the point 96 is higher than the point 98, part of the coating material will flow laterally on the frusto-conical portion 39 of the freely rotatable spindle 28 to be spread on the insole rib 10, while another portion will flow directly downward onto the work and be distributed by the brush 26. This brush, as may be seen from Fig. 10, is inclined rearwardly with respect to the direction of feeding movement of the work (see the arrow in Fig. 3) and, hence, the bristles thereof will be radically deflected by contact with the work, in accordance with the teaching of Letters Patent of the United States No. 2,208,694, granted July 23, 1940, upon the application of Joseph Barbati. Being so radically deflected, the bristles spring back more readily when relieved of contact with the work. It is found desirable to trim the lower end of the brush, as shown in Fig. 8, so that one portion 102 which bears upon the bottom of the channel is longer than the adjacent portion 104 which bears upon the mid-portion 106 of the insole. Artificial bristles made of Nylon filaments are found to have long-wearing qualities and to be more readily cleaned from coating material, such as latex or rubber cement, than are natural bristles. The bristles are retained within a brush back 108 which at its upper edge abuts a block 108 and is held against horizontal movement by an interlocking projection 107 (Fig. 8). The block 108 is attached to the far face of the nozzle by screws which also serve to hold a brush-retaining spring plate 110 (Fig. 10).

Coating material is supplied to the nozzle by the tube 34 (Fig. 3) which is clamped to a nipple

112 made separately and then press-fitted into the downward extension 86' of the horizontal lower portion 86 of the U-shaped block 82, which portion forms the front plate of the nozzle. The nipple is closed at its right end by a clean-out screw 114, and it has a squared portion 116 over which an upper arm 118 (Fig. 6) of the removable nozzle portion 90 is slipped. The arm 118 is integral with an upright portion 117. This removable nozzle portion 90 is then clamped against the fixed nozzle portion by a knurled nut 119 (Fig. 9) received on a threaded portion of the nipple. After the nipple has been press-fitted into the block portion 86, a hole is drilled through its upper wall to receive the valve rod 36, and a square-bottomed recess 87 is made in the inner face of the nipple. Another smaller hole 121 is drilled through this recess to provide a circular sharp-edge valve seat cooperating with the tapered end of the valve rod 36. This smaller drill hole 121 may extend slightly into the upper portion of the recess 92, but the dents formed as a result have no function.

This same U-shaped block 82 which carries the nozzle also provides a support for the rotatable spindle 28 and for the valve rod 36 (Figs. 3 and 5). The spindle 28 passes freely through the lower arm 86 of the block, and its up-and-down movement is limited by a pin 119' entering a groove in the spindle 28. The pin is carried by an adjustable plate 120 held in place by a screw 122 passing through a slot in the plate. The valve rod 36 passes through a stuffing box 124 (Fig. 10) and has an enlargement 126 (Fig. 5), received in a passage in the upper portion of the block 82, and a reduced upper portion 128 which passes through a screw 130 retaining a spring 132 which rests upon the enlarged portion 126 and urges the valve rod to closed position. Operation of the valve rod to open the valve is effected by means of a lever having a pivot 133 journaled in an outwardly-extending flange 134 (see also Fig. 7) provided upon the swinging frame 70. This lever has a short arm 136 clamped on the pivot 133 and which is forked to surround the valve rod beneath the enlarged portion 126. The lever also has a long arm 138, also forked, to surround a rod 140 forming part of a valve-operating mechanism.

The valve-operating rod 140 passes through top and bottom flanges 142 and 144 (Fig. 7) on the swinging frame 70 and is threaded to receive stop nuts 146 (Fig. 5) which limit the downward movement of the rod by engagement with the bottom flange 144. Another nut 148 underlies the forked end of the long lever arm 138, and the rod is surrounded by a spring 150 positioned between the upper flange 142 and the top of said arm. At its lower end, the operating rod 140 is provided with a pivoted latch 152 urged to the right by a leaf spring 154 (Figs. 1 and 5) and having a notch 156 which will catch on a rectangular abutment plate 160 also carried by the swinging frame 70 to hold the valve open in running position. The abutment plate 160 is secured to the lower end of a vertical carrier rod 162 the position of which may be adjusted by means of a nut 164 (Figs. 1 and 5) resting against the upper flange 142 (Fig. 7) of the swinging frame. Rotation of the rod in its abutment is prevented by a pin 166 (Fig. 5) in the rod which passes through a slot 168 in the far side of the swinging frame 70. At its lower end, the latch 152 has a cam roll 170 which may be engaged by the upper surface of a wedge-shaped cam 172. The cam 172 is formed on the upper end of an arm 174 attached by a bill

bolt 176 to a cross shaft 178 which is journaled in a bracket 180 attached to the frame.

Supported on the bracket 180 is an extension 182 on which there is carried a work table 184. It should be noted also, from Figs. 1 and 5, that a scraper plate 190 bearing against the lower feed wheel 22 to keep it clean is attached to an arm 192 which is supported on the under side of the swinging arm 50 and is held in position thereon by a screw 194. Gages for the guidance of the work in a direction at an acute angle to a plane normal to the axes of the feed wheel shafts and substantially normal to the length of the outlet opening 94 are secured to the upper wheel arm 42. These comprise an angle plate 196 (Fig. 3) held by a screw 197. This plate has an extension 198 having an end face 199 serving as a gage and also to support the insole rib so that it cannot be crumpled by the feed wheels. The extension is tapered at its far side so as to extend as close as possible to the two feed wheels. A depending gage 200 has a slotted shank 202 and is held by a screw 204. The gage 200 is effective to stop turning movement of the insole as it is swung rapidly around its toe end.

In order, now, that the operator may control the swinging of the bracket 70, the raising of the lower feed wheel arm 50 and the lifting of the valve rod 36, a control mechanism is provided which may be actuated by a treadle (not shown) connected to a treadle rod 210 (Figs. 1 and 2) which extends up through the column 46 and is connected to the mid-portion of a lever arm 212 which is secured to a rockshaft 214 journaled in the frame 44 of the machine and extending out through the left side thereof, as viewed in Fig. 1. Downward movement of the arm 212 is limited by a stop screw 216 as it engages the bottom of the frame 44, and this same arm is provided with an upwardly-extending rod 218 (Figs. 1 and 2) which passes through a block 220 received in an extension 222 of the pivoted lower arm 50 which carries the lower feed wheel 22. Surrounding the upper portion of this rod 218 is a spring 224 which rests against a washer on top of the block and, to provide a lost-motion connection, the rod 218 has a collar 226 which may be brought down against the spring, thereby resiliently to lift the lower feed wheel. Secured to the extension 222 of the wheel-carrying arm is a forked plate 228 which has abutment screws 230 and 232 cooperating with the upper and lower faces of a plate 234 secured to a part of the frame which forms a bearing for the drive shaft 60. These stop screws 230 and 232 are adjusted to provide the desired amount of separation of the lower feed wheel 22 from the upper feed wheel 20 when the machine is idle and to limit the approach of said wheels if the lower one is inadvertently raised when no insole is in place. The left end of the rockshaft 214 is provided with a lever 236 which is pinned to the shaft and which is, at its far end, loosely connected to an upwardly-extending rod 240 which has, at its upper end, a cylindrical crossbar 242 (Figs. 1 and 7) adapted to be received in a cupped end 244 (Fig. 5) of a lever arm 246 pinned to the pivoted rod 72 which supports the swinging frame 70. As the treadle rod 210 is depressed, the rod 240 is raised so as thereby to lift the lever 246 through a compression spring 250 surrounding the rod 240 and pressing down against a thumb nut 252 threaded thereon. By this arrangement, the lifting of the rod effects a yielding movement of the swinging frame 70 to carry the frusto-conical portion 30

of the spindle 28 against the inner side of the insole rib to hold the latter against the end face 32 of the upper wheel 20. This movement is limited, to avoid allowing the portion 30 to strike the feed wheel, by a stop screw 253 in the frame extension 78 and positioned to contact the top of the swinging frame 70. On the other hand, when the treadle is released, the rod 240 will move down, and the bar 242 at the upper end of it will engage the cupped portion 244 of the lever 246 positively to swing the frame 70 so as to carry the nozzle away from the rib 10 of the insole.

On the near end of the lever 236 is pivotally attached a short upstanding rod 254 which passes through a vertical slot in a lever arm 256 secured to the cross shaft 178. On this short rod is a transversely extending roller 258 which is received in an inclined slot 260 (see also Fig. 5) in the lever arm 256, thereby providing a freely acting yet firm connection between the treadle-operated lever 236 and the cross shaft 178 which carries the cam 172.

As a result of this arrangement of the control mechanism, the operator can, when presenting a piece of work supported on the table 184 with the toe end toward himself, so position this work that the end of the insole rib will lie between the spindle and the upper feed wheel, thus brining the feather 18 in position to be gripped by the two feed wheels. As he depresses the treadle connected to the treadle rod 210, however, the lower feed wheel will not be raised immediately because of the space between the collar 226 and the top of the spring 224, thus giving time for the upward movement of the rod 240 to release the swinging frame 70 and then to allow the spindle of the nozzle to grip the rib against the face of the feed wheel under the action of the spring 250. At substantially the same time, the cam 172 will be carried from the position illustrated in Fig. 1 to the position illustrated in Fig. 5. In so doing, the valve rod 36 will be raised momentarily by the treadle-operated control mechanism to allow an excess supply of coating material to flow into the nozzle and thus to insure an adequate supply at the outlet of the nozzle so that the coating operation will start as soon as the lower feed wheel has been raised into the gripping position which is shown in Fig. 5. During this normal feeding operation, the valve will be held open, after release by the cam, by reason of the engagement of the latch 152 with the abutment plate 160 and to a degree determined by the adjustment of the thumb screw 164 on the upper end of the rod 162 which carries the abutment plate. On the other hand, when the end of the insole rib nears the coating position, the operator will be able quickly to shut off the supply of cement as the insole is disengaged from the feed wheels, the reverse movement of the cam 172 being effective to knock the latch 152 from the abutment plate and to permit the instant closing of the valve. As soon as the valve 36 has closed, there will be such a small amount of cement in the recess 92 of the nozzle that there is substantially no danger that it will flow out through the outlet opening 94 and, with a little practice, the operator is able to draw the insole away from the spreading brush 29, thereby to limit the extent of the band of cement to a point at the end of the rib.

Having thus described my invention, what I claim as new and desire to secure by Letters Patent of the United States is:

1. In a machine for applying a coating pro-

gressively upon a piece of work, an applying device, and mechanism for momentarily providing an excess of coating material at the point of application at the beginning only of an operation upon the piece of work.

2. In a machine for applying a coating progressively upon a piece of work, an applying device, and operator-controlled means for regulating the supply of coating material to the device, including means for supplying a momentary excess of coating material at the beginning of an operation.

3. In a coating machine, an applying device, a driven work-engaging device, operator-controlled means for gripping a portion of the work against said driven device to cause feeding movement of the work, and means operated in timed relation to the movement of the operator-controlled means for momentarily changing the quantity of material supplied to the applying device as the work is gripped.

4. In a coating machine, an applying device, a slide valve controlling the supply of coating material to said device and having a normal operating open position, and operator-controlled means for opening said valve by sliding it beyond its normal operating position as the work is presented to the machine and then releasing the valve.

5. In a coating machine, an applying nozzle, a valve controlling the supply of coating material to the nozzle, and operator-controlled means for opening the valve to supply an excess of coating material and then returning the valve, after an interval, to an operating position where less coating material will be supplied.

6. In a coating machine, a nozzle, a spring-operated valve controlling the supply of coating material to the nozzle, means for retaining said valve against the force of the spring in a normal operating position, and operator-controlled means for opening the valve beyond the normal operating position and then allowing it to be brought back by the spring to normal position.

7. In a coating machine, a nozzle, a spring-operated valve controlling the supply of coating material to the nozzle, means for retaining said valve against the force of the spring in a normal operating position, and operator-controlled means for opening the valve and then releasing it to the action of said retaining means, whereby the open valve will be held open, unaffected by slight unintentional movements of the operator-controlled means.

8. In a coating device, a driven feed wheel, a work support, said wheel and support being mounted for relative movement, a coating device, means controlling the supply of coating material to that device, and operator-controlled mechanism arranged to cause a relative movement between the feed wheel and the support, thereby to cause them to grip the work and feed it, said means being also operative momentarily to increase the supply of coating material to the coating device as the work is gripped by the feed wheel.

9. In a coating machine, a coating device, a spring-operated valve for regulating the supply of coating material to that device, a latch for holding the valve in a normal open position, and means for pushing the valve beyond that normal position and then releasing it to the action of the latch.

10. In a coating machine, a coating device, a spring-operated valve for regulating the quantity of coating material supplied to the device, said

valve having a spring-operated latch, an adjustable abutment with which said latch cooperates to hold the valve open, means for adjusting the abutment, and means for moving said valve to latched position.

11. In a coating machine, a coating device, a spring-operated valve for regulating the quantity of coating material supplied to the device, said valve having a spring-operated latch, an adjustable abutment with which said latch cooperates, driven work-gripping means for feeding the work progressively past the coating device, one part of said gripping means being movable, and operator-controlled means for changing the position of the movable part of the gripping means to cause it to engage the work and moving said valve latch beyond said abutment and substantially immediately releasing it to engage the abutment without releasing the work.

12. In an insole coating machine, a work-engaging driven feed wheel, a movably mounted nozzle, a valve controlling the flow of coating material to the nozzle, and operator-controlled means for moving the nozzle to grip the work against the feed wheel and substantially simultaneously opening the valve.

13. In an insole coating machine, a work-engaging driven feed wheel, a nozzle movably mounted to grip a rib of the insole against said feed wheel as it coats one side of the rib, a valve controlling the flow of coating material to the nozzle, and operator-controlled means for moving the nozzle and opening the valve in timed relation to the movement of the nozzle.

14. In an insole coating machine, a driven work-engaging feed wheel, a nozzle, for coating one side of a rib of the insole, mounted for bodily movement to grip the rib between itself and the feed wheel, and operator-controlled mechanism controlling the supply of coating material to the nozzle and the bodily movements of the nozzle, said mechanism being also operative momentarily to supply an excess of coating material to the nozzle without interfering with the subsequent normal supply to the nozzle.

15. In a coating machine, a nozzle, a nozzle support movably mounted on the machine to carry the nozzle into engagement with the work, a valve for the nozzle mounted on said support, a valve-operating lever pivoted on the support, and means carried by the support for retaining the valve in open position.

16. In a coating machine, a nozzle, a nozzle support movably mounted on the machine to carry the nozzle into engagement with the work, a valve for the nozzle mounted on said support, a valve-operating lever pivoted on the support, and adjustable means carried by the support for retaining the valve in a predetermined open position.

17. In a coating machine, a coating device, a valve for controlling the supply of coating material to the device, valve-operating means including means for retaining the valve in open position, and a cam movable past said operating means momentarily to permit the passage of an excess supply to the nozzle and then to release the operating means for a return to its normal open position.

18. In a coating machine, a coating device, a valve controlling the supply of material to said device, spring-operated means urging said valve toward a closed position, and a cam movable into and forward in a continuous path out of engagement with the spring-operated means to cause

a momentary excess of coating material to be supplied to said device.

19. In a coating machine, a coating device, a valve controlling the supply of coating material to the device, a spring-operated member for closing the valve, a latch co-operating with said member to hold the valve in open position against the force of the spring, and cam-operated means for opening the valve beyond its latching position and then releasing it to the control of the latch.

20. In a coating machine, a nozzle, a valve controlling the supply of material to the nozzle, a spring-operated rod urging the valve to closed position, a roller on said rod, a latch for holding the rod in a position where the valve will be in normal open position, and a cam movable against and past said roller to move the valve beyond its normal position and then release it to the latch.

21. In a coating machine, a nozzle, a valve controlling the supply of material to the nozzle, a spring-pressed rod connected to said valve, a pivoted latch on said rod, said latch having a roller, and a cam movable to engage said roller to move the rod beyond the position necessary for engagement of the latch and then to release it.

22. In a coating machine, a nozzle, a valve controlling the supply of material to the nozzle, a spring-pressed rod connected to said valve, a pivoted latch on said rod, said latch having a shoulder, a cooperating abutment adjacent to the latch for engagement by said shoulder, a spring urging the latch toward the abutment, and a cam movable first to push the rod to allow the latch to catch on the abutment and movable then to knock the latch off the abutment.

HARRY PHILLIPS.
